PRODUCTION OF TEXTILE THREADS

Donald Finlayson and Ronald Bezant, Spondon,
near Derby, England, assignors to Celanese
Corporation of America, a corporation of Dela-
ware

Application November 23, 1938, Serial No. 242,012
In Great Britain December 4, 1937

5 Claims. (Cl. 57—157)

This application relates to the manufacture of textile threads and fabrics, and particularly to the manufacture of textile threads which are crimped along their length, and to the manufacture of mixed threads and fabrics containing such crimped threads.

In U. S. Patents Nos. 2,089,198, 2,089,199 and 2,111,211 processes and apparatus are described whereby a crimp may be imparted to textile threads along their length. In these specifications there are described, inter alia, processes wherein the crimp is imparted to the threads by false twisting the threads and continuously setting the false twist in the threads, e. g. by steaming the threads at a point where they are twisted. It is a characteristic of these false twisting processes that the thread is trapped at the false twisting device so that the false twist is substantially restrained from running past the trapping device. Thus in U. S. Patent No. 2,111,211 there are described as trapping devices wire hooks, wire loops, slotted discs, floating wire rings and the like.

The degree of crimping produced depends, especially as regards its permanence, on the degree of trapping effected in the false twist device, the higher the angle of contact of the thread with the false twist device, the more permanent the crimp. Permanence of crimp may also be increased by doubling the crimped yarns with other yarns adapted to take the major part of the tension imparted to the doubled yarn, and so preventing the crimp being pulled out of the crimped component. Thus, in U. S. applications S. Nos. 160,066 and 232,795 filed August 20, 1937, and October 1, 1938, respectively are described various composite yarns and methods of making them in which one or more yarns of crimped artificial filaments are doubled with one or more yarns capable of being shrunk relatively to the crimped yarns, after which the shrinkable yarns are caused to shrink so that subsequently they take the major part of the tension applied to the composite yarns. It has now been found, however, that by doubling two or more yarns, one or more having a more permanent degree of crimp than the rest, a similar effect appears to be produced, in that the more permanently crimped yarn may be employed to prevent the crimp being pulled out of the remaining component or components.

According to the present invention, therefore, a crimped yarn is produced by doubling together one or more crimped components having a higher or more permanent degree of crimp with one or

more components having a lower or less permanent degree of crimp. The resultant product is a yarn possessing very valuable wool-like qualities whose crimp has a high degree of permanence by reason of the fact that the more permanently crimped component takes the greater part of the tension to which the yarn is subjected. At the same time, the yarn is crimped throughout, and is therefore of a substantial homogeneous nature. In doubling the different components together it is preferable that the more permanently crimped component should be fed to the doubling operation at a lower rate than the other component.

15 A satisfactory yarn for use in the present invention as the more permanently crimped components may be obtained by the methods described in U. S. Patents Nos. 2,089,198, 2,089,199 and 2,111,211 if the angle of contact of the thread 20 leaving the false twisting device with the trapping device is greater than 90°, e. g. 180° up to 360° or more. Thus, especially satisfactory results may be obtained by using a wire hook or wire loop as the trapping device, e. g. as described in U. S. Patent No. 2,111,211 and instead of merely passing the thread under the hook or through the loop, causing the thread to lap round the wire of the hook or loop. The less permanently crimped components for use with 25 the components described above may be obtained by using the devices of any of U. S. Patents Nos. 2,089,198, 2,089,199 and 2,111,211 with an angle of contact at the trapping device less than 90°, or 30 they may be obtained by the action of hot aqueous media on cellulose acetate yarn, preferably containing filaments of flat cross-section.

35 The new process is of especial value in connection with the crimping of threads of cellulose acetate, but it may also be employed in the crimping of threads of other materials. Thus the threads treated may have a basis of an organic derivative of cellulose other than cellulose acetate, e. g. cellulose formate, cellulose propionate, cellulose butyrate, cellulose acetate-propionate or other organic ester of cellulose, methyl cellulose, ethyl cellulose, butyl cellulose, benzyl cellulose and other ethers of cellulose. The invention may also be applied to the treatment of threads of regenerated cellulose, such as viscose or cuprammonium artificial silk, or to the treatment of threads of natural textile materials, e. g. natural silk. Threads consisting of filaments of more than one of the above materials may also be treated.

40 45 50 55 55 The invention may be applied to a bundle of

smooth continuous filaments, in which case the resulting bundle may be used as a continuous filament yarn containing any desired twist appropriate to the use to which it is to be put, or may be transformed by cutting or otherwise forming into a spun fibre yarn. If the bundle is to be cut into staple fibres it should preferably contain little or no twist after the crimping operation so that the fibres can be easily separated in readiness for the subsequent spinning operation. Again the process may be used to crimp a spun yarn, i. e. a yarn containing fibres cut or otherwise formed into comparatively short lengths from continuous filaments. In crimping such a yarn sufficient twist should be retained after setting the crimp to maintain coherence of the yarn.

The crimped threads produced according to this invention may be converted into fabric form by weaving or knitting.

By way of example a form of apparatus for producing the component yarns to be employed in the present invention will now be described with reference to the accompanying drawing in which—

Fig. 1 shows in elevation a lay-out of an apparatus of the kind described in U. S. Patent No. 2,111,211 and adapted for carrying out the present invention;

Figs. 2 and 3 show a detail of the apparatus shown in Fig. 1 as employed respectively for producing the two components used in the present invention; and

Figs. 4 and 5 show in plan and elevation a modification of the same detail.

Referring to Fig. 1, in the apparatus shown the two yarns are being crimped simultaneously. The two yarns 1 and 2, which are substantially twistless yarns of straight continuous filaments of cellulose acetate, are drawn from two bobbins 3 and 4 through guides 5 and 6 and are conducted through a further guide 7 to a gate tensioning device 8. The yarns pass together over a roller 9 to a steam chamber which comprises a main steam pipe 10 adapted to supply a row of crimping devices. For each crimping device there is provided in the pipe 10 a nipple 11 through which the two yarns 1 and 2 enter and an off-set member 12 provided with a nipple 13 through which the two yarns 1 and 2 leave the steam chamber. Wet steam is supplied to the pipe 10.

The yarns leaving the steam chamber are drawn through the middle of a false twisting device 14 to be described in greater detail hereafter. The false twisting device 14 is mounted on a bracket 15 carried on a rail 16 secured to a frame 17 of a twisting machine. The false twisting device 14 is driven by means of a band 18 from a pulley 19 driven by means of a wharf 20.

On leaving the false twisting device 14 the yarns proceed together through a balloon guide 21 and then, passing upwards, are separated by means of a rod 22 which serves not only to separate the two yarns but also to remove any slight residual twist that might persist along portions of the yarns. The yarns now in the form of crimped yarns 23, 24 then pass separately over a guide 25 and partly round each of three draw rolls 26, 27, 28 in turn. The draw rolls 26, 27, 28 are rotated at constant speed and feed the crimped yarns 23, 24 to two bobbins 29, 30 which are driven at a constant peripheral speed lower than that of the rolls 26, 27, 28 to allow a slight contraction of the yarn.

The false twisting device 14 is of the kind described in U. S. Patent No. 2,111,211 and comprises on its upper surface a trapping device 32 shown in greater detail in Figs. 2 and 3. By varying the severity of action of the trapping device 32 yarns having different degrees of crimp may be produced. As shown in Figs. 2 and 3 the trapping device 32 is in the form of a hook. In Fig. 2 the yarn indicated at 33 is shown to proceed round the back of the hook before passing through it so that it is constrained to turn through a substantial angle on passing through the trapping device and makes substantial contact therewith. As shown in Fig. 3, on the other hand, the yarn 33 passes simply through the hook so that a smaller angle of contact is made as a result of which a lower degree of crimp is imparted to the yarn.

In Figs. 4 and 5 is shown a modification of the device shown in Figs. 2 and 3 in which an additional hook 34 is provided on the upper surface of the false twisting device 14. This hook 34 which serves to prevent ballooning of the yarn between the point 35, at which it issues from the top of the false twisting device 14, and the trapping device 32 may, as shown in Fig. 4, be offset from the straight line between these two points so as to provide a further trapping action.

In using crimped yarns produced by the means described above a very valuable wool-like yarn may be obtained by first doubling together three ends of cellulose acetate yarn of 140 denier which have been crimped by the use of the device in the manner illustrated in Fig. 2, then doubling together three ends of similar yarn which have been crimped by the method illustrated in connection with Fig. 3, then doubling together two ends of the product of the first of these doubling operations with one end of the product of the second of these doubling operations, the doubling twist being 5 turns per inch reverse, and finally doubling together two of the composite yarns so obtained with 4 turns per inch left-hand doubling twist.

The doubling twist employed will, in general, be quite low, e. g. about 5 turns per inch, in order to preserve as much as possible the voluminosity of the product, and where more than one doubling operation is employed, as in the example given above, it is desirable that the directions of the various doubling twists should be such that the final product has only a low degree of twist. Preferably one or more of the yarns is fed to the doubling device at a speed greater than that of the other yarn or yarns.

Having described our invention what we desire to secure by Letters Patent is:

1. Process for the production of a crimped yarn which comprises imparting a crimp to at least one component yarn, imparting a higher or more permanent degree of crimp to at least one other component yarn, and doubling together the plurality of components thus crimped, to form a composite crimped yarn.

2. Process for the production of a crimped yarn which comprises imparting a crimp to at least one component yarn, imparting a higher or more permanent degree of crimp to at least one other component yarn, doubling together the plurality of components thus crimped, to form a composite crimped yarn, and in the course of the doubling operation, feeding the component having a higher or more permanent degree of crimp at a lower rate than the remaining component.

3. Process for the production of a crimped yarn, which comprises submitting at least two component yarns to a false twisting operation, trapping each of said components during said false twisting operation so as to restrain the false twist from running past the trapping points, continuously setting the false twist in said components, one of said components being more severely trapped than the other in said false twisting operation so as to produce a higher or more permanent degree of crimp therein than in the other and doubling said components together.

4. Process for the production of a crimped yarn, which comprises submitting at least two component yarns to a false twisting operation, trapping each of said components during said false twisting operation so as to restrain the false twist from running past the trapping points, continuously setting the false twist in said components, one of said components being more severely trapped than the other in said false twisting operation so as to produce a higher or

more permanent degree of crimp therein than in the other, doubling said components together, and during said doubling operation feeding said more severely trapped component at a lower rate than the remaining component.

5. Process for the production of a crimped yarn, which comprises submitting at least two component yarns containing cellulose acetate to a false twisting operation, trapping each of said components during said false twisting operation so as to restrain the false twist from running past the trapping points, applying to said components, while they contain the false twist, a hot aqueous medium so as to set the false twist in said components, one of said components being more severely trapped than the other in said false twisting operation so as to produce a higher or more permanent degree of crimp therein than in the other and doubling said components together.
